UNITED STATES PATENT OFFICE.

FELIX EMILE VALOIS, OF HAVERHILL, MASSACHUSETTS, ASSIGNOR TO HAMEL SHOE MACHINERY COMPANY, A CORPORATION OF MASSACHUSETTS.

SOLE-LAYING MACHINE.

1,389,714.

Specification of Letters Patent. Patented Sept. 6, 1921.

Application filed May 6, 1918. Serial No. 232,739.

To all whom it may concern:

Be it known that FELIX E. VALOIS, a citizen of the United States, residing at Haverhill, in the county of Essex and State of Massachusetts, has invented certain new and useful Improvements in Sole-Laying Machines, of which the following is a specification, reference being had therein to the accompanying drawings.

10 This invention relates to improvements in sole laying machines, such machines being adapted to press a cemented outersole against the innersole of a shoe to thereby secure these parts in proper position for the subsequent operations of sewing, loose nailing, etc. While the devices of the present invention are especially intended for use with machines having the above described function, they are also to some extent applicable to other types of machine, such for example as certain varieties of sole-leveling machines.

15 In sole laying machines of the above character it is customary to employ a shoe-supporting jack and a resilient sole-pressing pad, such jack and pad being relatively movable to exert pressure between a shoe and a sole supported between the same. As the shank portion of a shoe is usually unsymmetrical, the curvature thereof being quite different upon opposite sides of a centrally disposed line from the toe to the heel, it has been customary, in order to secure a uniform pressure over the entire sole, with 20 consequent adhesion thereof to all parts of the innersole, to use a pressing pad of unsymmetrical form. The pad commonly employed is provided upon its shank-engaging portion with a pair of spaced apart humps 25 or ridges for engagement with the opposite side portions of the shank of the sole, these humps or ridges, however, being of unlike form and located one slightly nearer the heel portion of the shoe than the other in 30 order to conform to the shape of the shank of the shoe upon its opposite sides, as above described.

35 Shoes as manufactured, however, comprise widely different styles and shapes and it is therefore necessary to keep in stock a large assortment of sole-pressing pads having shank-engaging humps or ridges variously disposed in order to secure the best results in operation of the machine. To further complicate matters, it is necessary to

provide such pads in pairs, the complementary pads of a pair being shaped to correspond with right and left shoes.

The making of pads of unsymmetrical form is expensive and the keeping in stock 60 of a large number of pads of different shapes is undesirable. The present invention therefore provides for the employment in a machine of the above character, of symmetrical pressing pads with an arrangement 65 of parts whereby such pads may serve to operate successfully upon shoes of widely different styles, and whereby also, the same shape of pad may be employed for either right or left shoes.

70 In sole laying machines of that type in which either the shoe-supporting jack or the sole-pressing pad is moved through a uniform distance toward the other by power actuated devices for producing the necessary pressure between the parts, difficulty 75 is experienced, due to variations in thickness of the material operated upon or in the height of last employed for supporting the shoe, in securing uniformity in operation, 80 and the present invention contemplates the provision of mechanism for use in a machine of the type described whereby the shoe and sole are always subjected to the same pressure regardless of the height of last or 85 thickness of material.

85 Other and further objects and advantages of the invention together with desirable combinations of parts and details of construction will be hereinafter pointed out at 90 length and particularly set forth in the appended claims, reference being had to the annexed drawings for a full disclosure of the invention and in which,—

95 Figure 1 is a front elevation of so much of a machine of the type described as is necessary to show the improvements forming the subject matter of this invention,

Fig. 2 is a side elevation of the parts shown in Fig. 1,

Fig. 3 is a sectional plan view on the line a—a of Fig. 1,

Fig. 4 is a fragmentary rear elevation on a reduced scale illustrating the drive mechanism, and,

Fig. 5 is a vertical longitudinal section of Fig. 4.

100 Referring to the drawings by numeral, and wherein approximately one-half of the machine has been illustrated; the other half 110

being identical in construction and operation; the numeral 10 designates a frame or base member of any suitable construction, and 11-11 spaced vertical parallel guide rods mounted upon the same.

5 A pad-carrying cross-head 12 is provided between the guide rods 11-11 and is adapted for vertical sliding movement upon the same, said cross-head being guided in its 10 vertical movement upon guide rods 11-11 by upper and lower guide sleeves 14-14 and 13-13, respectively.

15 A cam-carrying plate 16 (Fig. 5) is mounted to reciprocate upon suitable guide rollers 17 within the frame 10 and below the cross-head 12. A crank shaft 18, journaled in the base or frame 10, imparts a lateral reciprocatory movement to the plate 16 and may be driven in any suitable manner.

20 Carried upon the face of the plate 16 is a cam block 19 designed to coöperate with a roller 20 carried adjacent the base of the cross-head 12, and to reciprocate said cross-head 12 vertically upon the guide rods 11-11 as the plate 16 is moved backward and forward by the crank arm 18.

25 A sole-pressing pad 21 is yieldingly supported upon cushion springs 22 within a cradle member 23, said cradle member being 30 supported for rocking movement upon the cross-head 12 by trunnions 24^a. The sole-pressing pad 21 is provided intermediate its heel portion 24 and toe portion 25 with a pair of oppositely positioned humps or 35 mounds 26, the contour of the surface of said sole-pressing pad 21, on either side of its longitudinal center line being symmetrical.

40 Slidably mounted for vertical movement upon the guide rods 11-11 through the medium of guide sleeves 28 is a second cross-head 27 of substantially the same length from front to rear as the sole-carrying pad 21, and adapted to be normally supported 45 upon nuts 27' upon guide rods 11-11.

45 Mounted upon the cross-head 27 and adapted to travel with the same is a composite shoe-supporting jack 29 comprising a heel member 30 and a toe member 31. 50 Heel member 30 and toe member 31 are adjustable toward and from each other upon a guide bar 32 by means of links 33, 34 pivotally connected to opposed arms 36 of a transverse lever 35 fast upon the lower end 55 of a vertical shaft 37. The shaft 37 is journaled in the cross-head 27 at a point directly above the center of sole-pressing pad 21, a hand wheel 38 being provided upon the upper end of said shaft. By turning the 60 hand wheel 38 any required adjustment of the heel member 30 and toe member 31 toward and from each other may be secured to allow for the proper positioning of shoes of varied sizes and shapes upon the jack.

65 The shoe-supporting jack 29 as a unit is

adapted for angular adjustment with relation to the sole-pressing pad 21 for the purpose of positioning the shoe at various angles upon said pad in order to properly register the humps or mounds 26 with the 70 respective high portions of the shank of the shoe upon which pressure is required. To this end the said guide bar 32 is pivotally mounted upon the under face of the cross-head 27 by means of a bolt 40 adjacent the 75 forward end thereof. At its opposite end said guide bar is held in any desired position of angular adjustment by means of a nut 41 upon the stud 42, said stud projecting through arcuate slots 43 in outstanding ears or lugs 44 formed upon the rearward end of the cross-head 27.

75 Means for producing the same amount of pressure upon shoes of different last and having soles of various thicknesses are provided, comprising the following devices.

80 Contact lugs 45-45 are suitably secured upon the guide sleeves 14-14 of the cross-head 12, and are adapted to move vertically 85 slidable rods 46-46 supported in guide brackets 47-47' secured upon the guide rods 11-11. At their lower ends the rods 46 are provided with adjustable collars 48^a which serve to limit the downward movement of said rods 46, and with retractile 90 springs 49 normally acting to retain the rods 46 in their downward position. Secured adjacent the upper ends of the rods 46 are cam blocks 48 provided with cam surfaces 50, said cam blocks being designed 95 normally to disengage locking dogs 51 from toothed racks 52 carried upon guide sleeves 28. The locking dogs 51 are each composed of two members 51^a, 51^b spaced apart to 100 embrace the cam blocks 48 and pivoted upon the guide brackets 47'. An anti-friction roller 51', mounted upon a pin 53, connects the said members 51^a, 51^b and against such roller the cam surface 50 of cam block 48 acts.

105 The operation of the device is as follows. Considering first the minimum thickness of last and sole upon which the machine is designed to operate, the cross-head 12, which is moved upwardly and downwardly 110 through a uniform distance by the forward and backward movement of the cam plate 16, rises upon the guide rods 11-11 until the sole-pressing pad 21 carried upon said cross-head 12 is in contact with the sole of the 115 shoe mounted upon the shoe-supporting jack 29, whereupon the contact lugs 45 engage the lower ends of the vertically sliding rods 46 to move the same in the guide brackets 47-47'. At this point the shoe-supporting jack 29 and the cross-head 27 move together with the cross-head 12 a slight distance, sufficient to allow the cam blocks 48, upon the rods 46, to clear the anti-friction rollers 51'. Locking dogs 51 are 120 125 130

then free to fall into the toothed racks 52 upon the cross-head 27 and lock the said cross-head 27 against any further upward movement. Further upward movement of 5 the cross-head 12 constitutes the pressure stroke.

If now shoes having lasts or soles of greater thickness (within certain limits) are placed in the machine, it will be seen that 10 they will receive the same amount of pressure from pressure pad 21, owing to the fact that such increase in thickness of last is compensated for by an increased vertical movement of the shoe-supporting jack and 15 the cross-head 27, prior to locking of the latter, the distance the cross head 12 travels, before the lugs 45 engage the ends of rods 46 being, however, constant, the cross-head 12 thus at all times traveling through the 20 same distance while exerting pressure upon the sole.

Owing to the relative angular adjustment of the shoe-supporting jack 29 and the sole pressing pad 21 various types and sizes of 25 shoes, either rights or lefts, may be operated upon without changing the pad 21 as has heretofore been necessary in machines of this character. It is obvious that by varying the 30 angular position of shoe jack 29 the effective position of the respective humps or mounds 26 of pad 21 with relation to the central transverse axis of a shoe supported upon said jack is so shifted that upon the upward movement of the pad-carrying mechanism 35 said humps or mounds will be caused to register with the desired portions of the shank of the shoe upon which pressure is required.

Having thus now described the invention, 40 together with a preferred embodiment of the same and the mode of operation thereof, what I claim and desire to secure by Letters Patent of the United States is,—

1. In a sole laying machine, in combination, a cross-head, a shoe-carrying jack provided with means for supporting the heel and toe portions of a shoe, and means for mounting said jack for pivotal adjustment upon said cross-head and about an axis adjacent the heel-supporting portion thereof on the opposite side of the cross head from 50 said toe support portion.

2. In a machine for laying soles, in combination, a cross-head provided with a bearing 55 surface upon its under side, and having a pivot pin near one extremity thereof and an arcuate slot near the opposite extremity thereof, a member pivotally mounted to turn about said pivot pin for adjustment upon said bearing surface, a bolt engageable with said member and slidable within said slot for guiding and holding said member in adjusted position, and a shoe-supporting jack carried by said member.

65 3. In a machine for laying soles employ-

ing a sole-pressing pad of symmetrical form, means for reciprocating said pad, a cross-head located above said pad and substantially coextensive in length therewith, a member pivoted near one end of said cross-head for angular adjustment upon the lower surface thereof, means for securing said member in adjusted position, guideways upon said member and a composite shoe-supporting jack comprising heel and toe-supporting members slidable upon said guideways and simultaneously adjustable toward and from each other.

4. In a sole laying machine having a sole-pressing pad and a shoe-supporting jack, a 80 frame-member, a pair of parallel guide rods fixed thereto, a pad-carrier slidable between and guided by said rods, a cross-head adjustably guided by said rods, a pair of ratchet members fixed to said cross-head, 85 pawls pivoted upon fixed supports and engageable with said ratchets, and automatically acting means for determining the engagement of said pawls and ratchets for fixing said cross-head in adjusted position 90 against movement away from said pad.

5. In a sole laying machine having a vertically slidable cross-head, in combination, means for automatically and adjustably fixing said cross-head against upward movement comprising a ratchet member fixed to the cross-head, a pawl engageable with said ratchet member and pivoted upon a fixed support, a pin projecting from said pawl, a vertically slidable rod, a cam member fixed 100 to said rod and engaging said pin, resilient means for positioning said rod whereby said cam serves normally to disengage the pawl from the ratchet, and means for moving said rod and cam to permit engagement of said 105 pawl with the ratchet.

6. In a machine for laying soles, a main frame, a pair of spaced, vertically extending rods fixed thereto, a sole-pressing pad carrier slidable upon said rods and provided 110 with an abutment, means for reciprocating said carrier, a cross-head having a shoe-supporting jack and provided with guide sleeves arranged to take over the respective rods and to be guided thereby, means for supporting said cross-head in its lowermost position, a ratchet fixed to one of said sleeves, a fixed bracket, a pawl pivoted to said bracket and engageable with said ratchet, said pawl having a pin projecting therefrom, 115 and a rod guided for vertical movement and having a cam member engageable with said pin for disengaging said pawl from the ratchet, said rod being engageable with said abutment upon the upward movement of the 120 latter for disengaging said cam from its pin, thereby permitting said pawl to lock the cross-head against upward movement.

7. In a sole laying machine, two members comprising a reciprocable sole pressing pad 130

and a reciprocable shoe supporting jack, means for reciprocating one of said members in a path of constant amplitude, and means whereby the other of said members is moved by said first member a limited extent and thereafter locked relative thereto while said first member reciprocates through a definite extent of its path.

8. In a sole laying machine, two members comprising a reciprocable sole pressing pad and a reciprocable shoe supporting jack, means for reciprocating said members together, and means for locking one of said members at a predetermined point while continuing the reciprocation of the other of said members in the same direction.

9. In a sole laying machine, two reciprocable pressure members, means for moving said members together in one direction, and means for locking the forward one of said members while the motion of the other continues, in such a manner as to lay the sole of a shoe held therebetween.

10. In a sole laying machine, two members comprising a shoe supporting jack and a sole pressing pad, means for moving one of said members toward the other of said members and thereafter moving the other of said

members therewith, and means for arresting the movement of said other member at a predetermined point while continuing the movement to a definite point of said one member.

11. In a sole laying machine, a sole supporting pad substantially symmetrical either side of its longitudinally center line, a shoe supporting jack relatively reciprocable toward and from said pad, and means whereby said pad and jack may be relatively adjusted to vary the operative relations thereof to conform to either a right or left shoe supported by said jack.

12. In a sole laying machine, a sole supporting pad having a plurality of substantially symmetrically arranged humps thereon, a shoe supporting jack relatively reciprocable toward and from said pad, and means for adjusting the operative relation of said jack and pad whereby said humps may be selectively, reversely, unsymmetrically related to a shoe supported on said jack to conform at will to right and left shoes.

In testimony whereof, he has signed his name to this specification.

FELIX EMILE VALOIS.
